FLUSH-ELL

Application filed September 24, 1929. Serial No. 394,912.

This invention relates to plumbing, and comprehends an improved "flush-ell" for use in connection with low down toilet combinations.

5 The one-piece or integral flush-ell which is now in general use in this combination has been open to certain objections and has possessed numerous disadvantages, notably, the time, labor and trouble involved when for 10 any reason it becomes necessary to disconnect the flush-ell. With the one-piece or integral flush-ell, it is absolutely necessary to remove the flush tank and this removal invariably causes damage to the supply tube, 15 ball cock, miscellaneous tank fittings or the tank itself. The removal of the tank is required whenever it is necessary to clear the T Y connection, the lead bend or a clogged trap; whenever it is necessary to replace the 20 bowl or hopper due to a cracked tongue, to replace a cracked bowl, a corroded flange or corroded bolts or cracked or washed away plaster; to solder a lead bend to a flange; to tighten a loose or badly fitting toilet spud 25 or to replace a worn out flush-ell.

In order to overcome the above recited disadvantages and to eliminate the objections noted, the present invention comprehends an improved flush-ell which is so constructed as 30 to permit of its connection and disconnection without disturbing the flush tank installation.

More specifically, the invention comprehends an improved flush-ell which is of sectional construction, the sections of which are connected by a flush joint union whereby when the sections are disconnected they may be separately removed from or applied to the hopper and flush tank respectively, 40 thereby eliminating the necessity of disturbing the installation of the same or their fittings.

The invention furthermore contemplates an improved flush-ell which is comparatively simple in its construction, does not materially increase its cost of production and which is highly efficient in its purpose.

With the above recited and other objects in view, reference is had to the following description and accompanying drawings, in

which there is exhibited one example or embodiment of the invention, while the claim defines the actual scope of the same.

In the drawings:

Figure 1 is a fragmentary sectional view 55 illustrating a flush ell constructed in accordance with the invention, in its applied position.

Figure 2 is an enlarged view illustrating 60 the manner in which the sectional ell is applied to or removed from the hopper and tank.

Referring to the drawings by characters of reference, A designates a toilet hopper of the modern type, the displacement of which 65 is limited to a direct upward movement due to a depending outlet tongue which protrudes below the floor level and which is provided with the usual inlet spud B for the water to flush the same and which spud B is threaded exteriorly at C to receive the nut D which impinges the packing ring or gland E against the end of the flush-ell which is telescopically received by the inlet spud B. In the present instance, the flush-ell, which is designated 70 generally by the reference character F, has opposite right angularly disposed ends or legs G and H, one of which leads or legs includes a removable or separable, exteriorly 75 smooth cylindrical section I, which section 70 is attached in the usual manner by the joint J to the flush tank. The extremity of the lead or leg H is formed with an outwardly projecting annular flange K, while the mating or confronting extremity of the removable section I is formed with an outwardly projecting annular flange L which is exteriorly 80 threaded at M. A nut N having an internal thread O is carried by the lead or leg H and is formed with an inwardly projecting flange 85 P which coacts with the flange K to limit its movement and prevent its displacement from the leg or lead H. The threads O of the nut N are designed to engage with the threads M of the flange L and, in practice, a gasket Q is arranged between the flanges K and L. This construction and arrangement affords a flush joint union 90

95 or connection between the removable section I and the lead or leg H which permits 100

when the union is disconnected, the separate removal or insertion of the flush-ell sections to avoid disturbing the installation of the hopper or flush tank R.

- 5 In practice, when the job requires only the removal for replacement of the flush-ell F, the water supply to the tank is not required to be cut off, nor is the drainage of the flush tank necessary. The plumber is required
10 only to unscrew the nut N and allow the same to drop below the upper flanged extremity K of the lead or leg H, after which the flush-ell F, with the exception of the section I, may be removed by loosening the nut D. Obviously, if necessary, the section I may then be removed by displacing the same directly downward. In practice, the joint or union may occur either in the leg or lead H as illustrated, or the leg or lead G. In installing the
15 new flush-ell or replacing an old one, the detachable section I is first positioned and attached and then the remaining portion of the ell is applied and the union established.

What is claimed is:

- 20 Means for connecting a proximately related flush tank and toilet hopper, said hopper being of the type connectible with upstanding floor studs, said means including a pair of angularly disposed legs with separable coupling means therebetween, the free ends being adapted to slidingly engage the outlets of the hopper and tank respectively, whereby the loosening of said coupling means permits sliding of the free ends of the
25 legs into said outlets to enable disassociation of the legs without disturbing the tank outlet connection, the sliding of the leg in the tank outlet enabling vertical and lateral displacement of the hopper from its studs, and
30 means for sealing said legs in said outlets after the connection has been made.

MAURICE FETTERMAN.
